CLAIM

The ornamental design for a shelving unit, as shown and described.

DESCRIPTION

FIG. 1 is a front perspective view of an embodiment of the shelving unit;

FIG. 2 is a front perspective view thereof and showing items in place in dotted line;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front perspective view of a second embodiment of the structure;

FIG. 10 is a front perspective view thereof and showing items in place in dotted line;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is a front perspective view of a third embodiment of the structure;

FIG. 18 is a front perspective view thereof and showing items in place in dotted line;

FIG. 19 is a front elevation view thereof;

FIG. 20 is a rear elevation view thereof;

FIG. 21 is a right side elevation view thereof;

FIG. 22 is a left side elevation view thereof;

FIG. 23 is a top plan view thereof;

FIG. 24 is a bottom plan view thereof;

FIG. 25 is a front perspective view of a fourth embodiment of the structure;

FIG. 26 is a front perspective view thereof and showing items in place in dotted line;

FIG. 27 is a front elevation view thereof;

FIG. 28 is a rear elevation view thereof;

FIG. 29 is a right side elevation view thereof;

FIG. 30 is a left side elevation view thereof;

FIG. 31 is a top plan view thereof; and,

FIG. 32 is a bottom plan view thereof.

The broken lines are for the purpose of illustrating the environment of the article only and form no part of the claimed design.

The shelving unit is shown with symbolic breaks. Any portion between the break lines forms no part of the claimed design.
